UNITED STATES PATENT OFFICE.

ROBERT WERNER, OF HOBOKEN, NEW JERSEY.

DESIGN FOR A TRIMMING.

Specification forming part of Design No. 11,186, dated May 6, 1879; application filed March 19, 1879.
[Term of patent 7 years.]

To all whom it may concern:

Be it known that I, ROBERT WERNER, of Hoboken, in the county of Hudson and State of New Jersey, have invented a new and original Design for Trimming, of which the following is a specification.

Figure 1 is a face view of my new design; Fig. 2, a cross-section of the same.

Similar letters of reference indicate corresponding parts in both figures.

This invention relates to a new shape or configuration of embossed and partly-fluted trimming used for dresses and other purposes.

It consists, principally, in arranging a row of prominent oblong projections directly between and adjoining two rows of ordinary fluting; also, in the new shape or configuration of border applied to fluted trimming, as hereinafter more fully specified.

In the accompanying drawings, the letter A represents a strip of fabric having the shape or configuration of my new design. It is shown to contain a row of prominent oblong projec-

tions, a a, between two rows, b and c, of ordinary fluting and parallel thereto. The outer border, d, at one side of the strip A, is plain fluting, separated by a plain depression, e, from the row b of fluting. The other border, f, of the strip A is ruffling on a narrow row of fluting, g, which is separated from the row b by a plain depression, h, as shown.

The design is produced by embossing or fluting machinery.

I claim—

1. The design for a fluted trimming, consisting of the rows b c of ordinary fluting, and the intermediate row, a, of oblong projections, substantially as shown and described.
2. The design for a fluted trimming, consisting of the ruffling f, fluting g, plain depression h, and fluting b, substantially as shown and described.

ROBERT WERNER.
